US00D833278S

(12) **United States Design Patent** (10) **Patent No.:** **US D833,278 S**
Pellerin et al. (45) **Date of Patent:** **** Nov. 13, 2018**

(54) **CLOSURE FOR A CONTAINER**

D226,555 S	3/1973	Weber
3,823,841 A	7/1974	Lovejoy
3,892,326 A	7/1975	Schneible
3,920,141 A	11/1975	Bojardi
3,944,102 A	3/1976	Grau et al.

FIG. 1 is a perspective view showing a closure for a container of our invention;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines depict portions of the closure for a container that form no part of the claimed design.
